CONSTRUCTION OF FIGURINES

Allan Morgan, Wyandotte, Mich., assignor to All Metal Products Company, Wyandotte, Mich., a corporation of Delaware

Application November 13, 1950, Serial No. 195,245

8 Claims. (Cl. 46—151)

1

This invention relates to ornamental devices and more particularly to figurines adapted for decorative and ornamental use, as playthings and for similar purposes.

It is an object of the present invention to provide a novel construction for a figurine or a similar ornamental device, which affords a highly pleasing appearance and which may be adapted for widely varied types of designs.

It is another object to provide a figurine construction which achieves the decorative effect of contrasting color designs on the apparel and body portions of the figures depicted without the necessity of delicate and expensive painting or other operations to achieve this decorative effect. More particularly, it is within the contemplation of this invention to provide a construction wherein the decorative effect of contrasting colors is achieved merely by assembling the ornament, without necessity of any further operations.

It is also an object to provide a figurine construction which allows the ornament to be quickly and easily fabricated using conventional manufacturing methods and materials, and in which the elements of the figurine may be rapidly assembled even by unskilled operators.

Other objects and advantages of the invention will become apparent upon consideration of the present disclosure in its entirety.

In the drawings:

Fig. 1 is a front elevational view of a preferred embodiment of the invention, showing the elements in their assembled relation;

Fig. 2 is a rear elevational view of the embodiment of Fig. 1;

Fig. 3 is a cross-sectional view taken along the line 3—3 of Fig. 1, and showing the relation of the front and rear sections of the ornament;

Fig. 4 is a front elevational view of the front section of the figurine;

Fig. 5 is a front elevational view of the rear section thereof;

Fig. 6 is a front elevational view of a second embodiment of the invention, showing the parts in assembled relation;

Fig. 7 is a rear elevational view of the embodiment of Fig. 6;

Fig. 8 is a front elevational view of the front section of the figurine of Figs. 6 and 7;

Fig. 9 is a plan view of the hat member;

Fig. 10 is a front elevational view of the rear section of the figurine; and

Fig. 11 is a cross-sectional view taken along the line 11—11 of Fig. 6, showing the relation of the front and rear sections.

The figurine comprises in general a front section 21 and a complementary rear section 22 which when in assembled condition are in contiguous relation and blend together to depict a human or other figure. These sections may be constructed of various materials, either plastic

2

or metallic. Any of the conventional molding methods, such as die-casting or injection molding may be used to form the sections. The two sections are constructed of materials having contrasting colors; for example, the front section 21 may be white and the rear section 22 red. The front section 21 is shaped to the contour of the front portion of the figure depicted, and the rear section 22 is correspondingly shaped to the contour of the rear portion of the figure. In general, each section in the illustrated embodiment comprises a relatively flat intermediate portion 23 which has formed in relief thereon various body sections and articles of apparel, and two curved side portions 24, which will blend with the curved side portions of the complementary section, the edges of the sections (not designated) being in flush relation. The inner surfaces 25 and 26 of the sections 21 and 22 respectively may be of concave shape to facilitate their manufacture and save material, although these surfaces may be in flush relation if desired.

The figurine of the embodiment illustrated in Figs. 1 to 5 is of a circus clown, although it will be understood that the principles of the invention are not limited to any particular figure but may be applied to widely varying types of ornaments. It will be seen, especially from Figs. 4 and 5, that the front section 21 incompletely shows the front portion of the clown in that only some of the apparel and bodily features which normally are seen from the front are formed as part of section 21. In particular, it will be seen from Fig. 4 that section 21 shows the costume 27 of the clown and also has formed thereon head 28. However, section 21 does not show the hands, feet, nose, eyes and mouth, nor does it show the bow-tie, buttons or crescent-shaped decorations on the costume. Instead, a series of spaced-apart aperture 29 having the cross-sectional form of these various features extends through front section 21. These elements are, however, formed on section 22 which is shown in Fig. 5. It will be seen from this figure that section 22 has formed thereon a series of spaced-apart projections having the cross-sectional shape of features which are omitted from section 21. In particular, section 22 has formed thereon projections depicting hand portions 30, feet 31, a costume hat 32, eyes 33 and nose and mouth 34. In addition, there are projections for a bow tie 35, buttons 36 and crescent-shaped decorations 37. All of these features extend forwardly from the main portion of section 22 and are of such size that when the sections are assembled they will be in contiguous relation with the exposed surface of front section 21, thus showing features of contrasting color on the front of the clown. For example, Fig. 3 shows a button projection 36 extending through a corresponding aperture 29 in the front section and a crescent-shaped pro-

jection 37 extending through another corresponding aperture. The relative sizes of the projections and apertures are such that the projections will have a snug fit, so that by merely pressing the front and rear sections together the figurine may be assembled for permanent use. It is thus unnecessary to apply glue or any other adhesive material to the parts in order to complete their assembly. It will be seen from Fig. 1 that when in assembled condition a highly decorative effect is achieved by the contrasting colors on the apparel and in the bodily features of the figurine.

Figs. 6 through 10 illustrate another embodiment of the invention showing the adaptability of the construction features to different types of ornaments. In this embodiment a cowboy is shown formed of a front section 38 and a rear section 39. The front and rear sections may have facing surfaces (not designated) which are in flush relation and the front section 38 has formed thereon a head portion 41, a vest portion 42, hands 43 and chaps 44. The head portion is provided with a pair of lugs 45, and an apertured portion 46 in the form of an exposed portion of a shirt is provided within the lateral confines of vest 42. The rear section 39 has formed thereon arm portions 47, legs 48, feet 49, and a projection 51 of the same shape as aperture 46. When the front and rear sections are assembled as shown in Figs. 6 and 7 it will be seen that the arms 47 will be in contiguous relation with the hands 43 on the front section, and that the legs 48 in conjunction with the chaps 44 of contrasting color will impart a realistic appearance to the costume. Projection 51, which is of the same color as sleeves 47 will appear as an exposed shirt portion within vest 42, and since this projection fits snugly within aperture 46 it will hold the front and rear sections firmly together. A costume hat 52 of color contrasting with that of front section 38 may be provided, the hat having openings 53 at the base of the crown for receiving lugs 45 so as to hold the hat firmly in place. It will be observed that lugs 45 will be visible through openings 53, thus giving the effect of decoration, bows or the like, of contrasting color on the band 54 of the hat.

While it will be apparent that the preferred embodiment of the invention herein disclosed is well calculated to fulfill the objects above stated, it will be appreciated that the invention is susceptible to modification, variation and change without departing from the proper scope or fair meaning of the subjoined claims.

I claim:

1. In a figurine construction, a front section shaped to the contour of the front portion of the figure depicted and having an exposed front surface, an article of apparel formed in relief on said front surface, an apertured portion of non-circular cross-section extending through said front section within the lateral confines of said article of apparel, said aperture being in the shape of a decorative element, a rear section of contrasting color to said front section shaped to the contour of the rear portion of the figure depicted, and a projection extending forwardly from said rear section, said projection fitting within said aperture to present a decorative element of contrasting color on said exposed front surface.

2. The combination according to claim 1, said projection having a snug fit within said aperture, whereby front and rear sections are held in contiguous relation.

3. As an article of manufacture, a figurine comprising complementary front and rear sections of contrasting colors and shaped to the contour of the figure depicted, said sections having mating surfaces, one of said sections having formed in relief thereon a bodily feature of the figure, the other of said sections having formed thereon an adjacent bodily feature, a non-circular aperture extending through said first section within the lateral confines of said first bodily feature, said aperture being in the shape of a portion of an article of apparel, and a projection of corresponding shape extending from said second section and fitting snugly within said aperture, whereby said adjacent bodily features will be held in contiguous alignment.

4. The combination according to claim 3, the outer end of said projection extending substantially to the surrounding surface of said first section, whereby an apparel portion of contrasting color is presented thereon.

5. The combination according to claim 3, further provided with a head portion formed on one of said sections, a plurality of retaining lugs on said head portion, a hat member of contrasting color fitting on said head portion, and a plurality of apertured portions on said hat member, said retaining lugs being received within said apertures, whereby elements of contrasting color are visible on said hat member.

6. As an article of manufacture, a three-dimensional figurine with hands and sleeves comprising complementary front and rear sections of contrasting colors and shaped to the contour of the figure depicted, said sections having mating surfaces in flush relation, one of said sections having formed in relief thereon hand portions of the figure, the other section having formed thereon the sleeve portions, at least one of said two portions extending beyond its corresponding mating surface, and means for securing said sections together in assembled relation, said hand portions being in contiguous alignment with said sleeve portions.

7. The combination according to claim 6, said securing means comprising an apertured portion in one of said sections, the aperture being in the shape of an element of apparel, and a projection on the other of said sections and extending in snug relation within said aperture, whereby the outer end of said projection presents an apparel element of contrasting color to said apertured portion.

8. As an article of manufacture, a figurine comprising complementary front and rear sections of contrasting colors and shaped to the contour of the figure depicted, said front section having formed in relief thereon a head portion having an aperture, said aperture having the shape of one of the features in the head, and a projection on said rear section and extending forwardly through said aperture, said projection being of shape corresponding to said aperture, whereby a feature of contrasting color is visible on said head.

ALLAN MORGAN.
